UNITED STATES PATENT OFFICE.

JOHN HOWES, OF WORCESTER, MASSACHUSETTS.

STOP-COCK.

SPECIFICATION forming part of Letters Patent No. 280,829, dated July 10, 1883.

Application filed June 17, 1882. (No model.)

To all whom it may concern:
Be it known that I, JOHN HOWES, of Worcester, in the county of Worcester and State of Massachusetts, have invented certain new and useful Improvements in Stop-Cocks; and I declare the following to be a description of my said invention, sufficiently full, clear, and exact to enable others skilled in the art to which it appertains to make and use the same, reference being had to the accompanying drawings, which form a part of this specification.

The object of my present invention is to provide a practical, durable, and convenient stop or plug cock for water-service pipes and for similar purposes, which shall obviate the ordinary objections of leakage at the top and bottom ends of the plug, after slight use, and stiffness of action when turned. These objects I attain by the mechanism herein shown and described.

Figure 1 is a side view of my improved stop-cock. Fig. 2 is a longitudinal vertical section of the same. Fig. 3 is a transverse vertical section at line *x x*. Fig. 4 is a horizontal section at line *y y*; and Fig. 5 is a horizontal section at line *z z*, or a plan of the spindle-disk. Fig. 6 is a longitudinal vertical section, showing the passages to the upper and lower chambers formed along the valve-seat. Fig. 7 is a horizontal section at line *w w*, Fig. 6.

In referring to the drawings, *A* denotes the body or shell of the cock, provided with attaching-bosses *p p* at its ends, and having a central valve seat or cylinder properly bored out internally for the reception of the conical plug *B*, which is made somewhat shorter than the seat-cylinder, and is located so as to leave chambers *e* and *f* between the ends of the plug and the ends of the cylinder. A screw-cap, *C*, fits onto and closes the top opening of the shell. The operating-spindle *D*, which passes through the center of the cap *C*, is provided with a flange or disk, *D'*; which rests against a packing-disk, *E*, on the under side of the cap and forms a close joint therewith. The spindle or stem *D* is formed separate from the plug *B*, its lower end being fitted to engage with the plug for rotating it without being attached thereto, so that the parts are permitted longitudinal movement independent of each other, while they are connected as regards rotative movement. This connection is made,

in the present instance, by the rectangular end of the spindle entering a square hole in the head of the plug; but other equivalent connection 55 may be used, if desired. The plug *B* is made so as to close and open the passage *a* by partial revolution. It may be provided with an internal chamber and side port, *i*, in addition to the direct water-way or ports *b*, to match 60 the passage *a* at one end when the passage *a* at the opposite direction is shut off. A vent or waste-passage, *F*, is formed at one side through a suitable boss or projection, *F'*, and a screw-plug, *G*, is arranged for closing and 65 opening said waste-passage, as illustrated. A portion of the periphery of the disk *D'* may be cut away, and a pin, *H*, fitted in the edge of the shell, to serve as a stop when opening and closing the cock. A small channel, *I*, is formed 70 from the lower chamber, *e*, to the passage *a* on the delivery side, to allow water to escape from beneath the plug *B*. Water can also pass up into the chamber *f* through the head of the valve, or through a passage formed in the shell 75 or seat alongside the valve, as indicated at *J*, Figs. 6 and 7, so that the pressure will force the disk *D'* firmly against the packing *E* and make a close joint therewith, while the valve *B*, being independent of the spindle, remains 80 in proper position on its seat. The pressure of the water, when the passage is closed, acting upon the plug, forces it into its seat with more or less pressure, according to the height 85 of the column of water from which the pressure is derived; but, when the valve is open and the pressure of water is equally distributed, the valve or plug is substantially balanced, and there is no tendency for the water to press out between the plug and its seat to cut a rut along 90 the adjacent surfaces, causing leakage and permitting the escape of water, as is the case with the ordinary plug-cocks.

The bottom end of the cylinder at *A*² can be cast integral or without an opening; or, if preferred, and to facilitate manufacture, it can be formed with an open end, and be afterward tightly closed by a screw-plug when the parts have been fitted and the inner surfaces properly finished.

What I claim as of my invention, and desire to secure by Letters Patent, is—

1. A stop-cock, constructed substantially as hereinbefore described, consisting of the body-

- cylinder A, closed at its bottom A², and having connecting-bosses p, with passages a, the conical plug-valve B, arranged within said cylinder, with its ports communicating with said 5 passages a, the independent handle-spindle D, interlocking with said plug, and provided with a broad flange or disk, D', within the cylinder-chamber f, the cap-piece C, and the packing-disk E, severally constructed and arranged as 10 shown, and for the purposes set forth.
2. In combination with the shell A, plug-valve B, and handle-spindle D, arranged as described, the side vent, F, and the stopper or valve G, as and for the purpose set forth.
- 15 3. In a stop-cock, a body-cylinder and a plug-

valve, constructed and arranged as described, with a water-chamber, f, above the plug, communicating with the supply-passage by a channel, J, along the seat, or through the valve-head, and a chamber, e, beneath the plug, provided with a channel, I, leading from said chamber into the delivery-passage, as and for the purposes set forth. 20

Witness my hand this 12th day of June, A. D. 1882.

JOHN HOWES.
